W. R. Lockhart

Walter R. Lockhart INVENTOR.

BY
Frank P. Weston
ATTORNEY.

UNITED STATES PATENT OFFICE.

WALTER R. LOCKHART, OF BROOKLYN, NEW YORK.

LEGGING.

1,317,167.

Specification of Letters Patent. Patented Sept. 30, 1919.

Application filed July 1, 1916. Serial No. 107,034.

To all whom it may concern:

Be it known that I, WALTER R. LOCKHART, a citizen of the United States, residing at the borough of Brooklyn, city of New York, 5 county of Kings, and State of New York, have invented certain new and useful Improvements in Leggings, of which the following is a specification, reference being had therein to the accompanying drawings, 10 which form a part thereof.

My invention relates to leggings and more particularly to a type thereof adapted to be spirally wound upon the leg of the wearer and to be made of felt.

15 Heretofore, there has been successfully used a fabric spiral legging or puttee formed of a strip of knitted fabric so shaped that in winding, it will conform to the contour of the leg. This type of legging or puttee has 20 been found to be highly satisfactory since it is light of weight, does not chafe the wearer and is more sanitary than leather or canvas leggings. A fabric legging has the further advantage that it affords ample support to the leg muscles and even with the 25 most severe usage has no tendency to contract or shrink in a manner to interfere with the free circulation of the blood in, or the pliability of the muscles of, the leg.

30 In those leggings of the type above referred to, which have been heretofore used, no provision has been made for holding the bottom of the legging in proper relation to the shoe of the wearer, either for facilitating the application of the legging, or preventing its creeping upwardly while in use, and the securing means for fastening the 35 top of the legging has not been such as to facilitate the quick application of the legging to the wearer or for securing permanency in the operative effect of the securing means.

In a legging or puttee made in accordance with my invention, one edge of the strip of 45 which the legging is formed is provided with means adapted to be connected with the top opening of a shoe in a manner to hold the end of the legging in the proper position to permit of the winding of the strip about 50 the leg of the wearer, thus not only facilitating the application of the legging, but holding the lower end thereof in a position fixed as to the top of the shoe, while the legging is being worn. Furthermore, the legging is 55 reinforced adjacent said means in a manner to protect the legging where it engages the

top of the shoe. The other end of the legging is provided with means whereby the top of the legging may be firmly and quickly secured to the body of the legging while permitting sufficient adjustment to compensate for that slight variance in the measurements of the calf of the leg in different persons, so as to permit the production of leggings of a standard size for general use.

60 A legging made in accordance with my invention is preferably made of a woven fabric so cut and finished as to impart thereto the desired degree of elasticity to promote comfort to the wearer.

70 The invention consists in such novel features of construction and combination of parts as are hereinafter set forth and described and more particularly pointed out in the claims hereto appended.

75 Referring to the drawings:

Figure 1 is a perspective view of a legging embodying my invention applied to the leg of the wearer, a portion thereof being broken away to disclose the manner of connecting the bottom of the legging to the shoe 80 of the wearer;

Fig. 2 is a view of the legging upon a smaller scale lying flat;

Fig. 3 is a view of the opposite ends of 85 the legging, the portion intermediate said ends being broken away; and

Fig. 4 is a view of one end of the legging 90 illustrating a modified form of securing means for the top thereof.

Like letters refer to like parts throughout the several views.

In the embodiment of my invention shown in the drawings, *a* indicates a continuous strip of fabric so shaped as to be readily 95 wound spirally, the central portion intermediate the ends of said strip being widened as shown. Preferably said strip is formed of a woven fabric, the strip being cut on the bias so as to impart flexibility in the direction of the length of the strip. After being cut one edge of the strip, the inner edge of Fig. 2, is shrunk and both edges thereof are provided with edge stitching for the two-fold purpose of holding the form of the legging and preventing raveling. I prefer to use the edge stitching instead of binding the edges, since the stitches are practically invisible and a better finish in the article is secured.

105 110 115 Carried by one end of the strip *a* is a hook *b* or other means adapted to engage the edge

of the front opening of a shoe in a manner to permit the lowermost loop of the legging when applied to the wearer to be held in a position fixed with relation to the shoe both 5 while the legging is being wound upon the leg and after it has been so wound. By using a small hook as shown in the drawings, an effective grip is secured upon the shoe, thus permitting the use of both hands 10 in winding the legging.

The other end of the strip *a* is provided with fastening means so that when the legging is completely wound, the top thereof may be secured in position. Preferably this 15 fastening means consists of a tongue *c* and a buckle *d* carried by a strip *e*, the tongue preferably being attached to the end of the strip and the buckle attached to the outer face of the strip sufficiently distant from the 20 end to permit less than one loop of the strip to intervene between the buckle and the end of the strip. Any desired form of buckle may be used, that shown in the accompanying drawings being a well known type of 25 friction buckle. By the proper spacing of the buckle with relation to the end of the strip *a*, sufficient latitude for adjustment to accommodate the legging to different users is afforded. In practice it has been found 30 that the amount of adjustment required is not great.

One edge of the strip *a* adjacent the hook *b* is provided with a reinforced wear strip *f* (as indicated in Fig. 3 of the drawings), 35 this strip in applying the legging following and bearing upon the top of, the shoe upper in a manner to prolong the life of the legging by protecting this portion thereof against chafing against the top of the shoe. 40 The end of the strip adjacent the tongue *d* is preferably reinforced as shown in Figs. 2 and 3.

Referring now to the form of the invention illustrated in Fig. 4 the securing means 45 for the top of the legging is shown as consisting of a tab *g*, having a button hole therein, secured adjacent the end of the strip *a*; a button *h* being secured upon the outer face of said strip in a position where it will 50 coöperate with the tab *g* when the legging is mounted upon the leg of the wearer. The end of the strip is reinforced as shown in Fig. 4. This reinforced end is provided with one member *i* of a snap clasp, the other 55 member *j* of which is carried adjacent the button *h* and between it and the end of the strip. The relative position of the button hole in the tab and the clasp member *i* and the button *h* and the clasp member *j*, should 60 be the same. In this form of the invention the end of the strip beyond the tab *g* serves as a guard to protect the securing means and at the same time causes a neat finish to the legging when in use.

65 For military purposes, the form of leg-

ging shown in Figs. 1 to 3 is preferable, since the tongue and buckle construction affords greater permanency in the securing means at the top of the legging. For other uses where dressiness is of greater importance, the form of the invention shown in Fig. 4 might be preferable. In this form of the invention, the difficulty of quick adjustment of the legging to different persons is greater than in the form shown in Figs. 75 1 to 3, since such adjustment can be secured only by shifting the button *h* and clasp member *j* upon the strip.

When the legging is not in use it may be conveniently rolled or folded in compact 80 form, and can be stored in a knapsack or other kit. When it is desired to don the leggings, however, it is merely necessary to engage the hook *b* with the top of a shoe and to wind the legging spirally about the 85 leg, drawing it taut as it is being thus wound, and unwound from the roll. The form of the strip, will make any particular care in winding it unnecessary, and when the strip has been entirely wound, it is merely necessary to utilize the securing means 90 above described for securing the free end of the strip about the leg above the calf thereof. When this securing means consists of a tongue and buckle as shown in Figs. 1 to 3, the top of the legging may be drawn, 95 by means of the tongue sufficiently tight to secure the desired fit. When a button hole and button is used, however, the buttons must be accurately set in position to secure 100 the desired fit.

In use, leggings made in accordance with my invention serve as a support for the leg muscles while affording sufficient ventilation and having sufficient absorptive properties 105 to secure comfort to the wearer. The flexibility inherent to the strip *a* affords sufficient pliability to avoid chafing or binding of the leg.

The legging may be readily washed without losing its shape or flexibility.

It is not my intention to claim broadly a legging consisting of a fabric strip since such are old and well known in the art. I believe it to be new, however, to provide a 115 legging of that type, wherein means are provided for holding the bottom thereof in a position fixed with relation to the shoe while the legging is being applied and after it has been applied. I also believe it is new to 120 provide a legging wherein the top thereof is provided with permanent adjustable fastening means.

It is not my intention to limit the invention to the precise details of construction 125 shown in the accompanying drawings, it being apparent that such may be varied without departing from the spirit and scope of the invention.

Having described the invention, what I 130

claim as new and desire to have protected by Letters Patent is:—

A legging consisting of a strip of woven fabric cut on the bias and adapted to be 5 spirally wound about the leg, a reinforcing wear strip secured to one end portion of said strip of fabric, a hook secured to said end portion and adapted to engage the edge of the front opening of a shoe, and adjust-
10 able means carried by the other end portion of said strip of fabric whereby the legging

may be secured in position upon the leg of a wearer and the unwinding of said strip of fabric is prevented.

In witness whereof I hereunto affix my 15 signature, in the presence of two subscribing witnesses, this 26th day of June, 1916.

WALTER R. LOCKHART.
